TRAFFIC LIGHT HOLDER

Henry C. Pfaff, Jr., Summit, N.J., assignor to Pfaff and Kendall, Newark, N.J., a corporation of New Jersey

Original application October 16, 1951, Serial No. 251,475. Divided and this application April 5, 1956, Serial No. 576,474

2 Claims. (Cl. 248—221)

This invention relates to devices used for connecting traffic light units to horizontal supporting frames which, in turn, are conventionally secured to vertically disposed poles for the control of approaching lines of traffic.

The object of this invention is to provide a traffic light unit of novel structural features which enable it to be adjusted to present the traffic light units at precisely the desired angles.

The invention is particularly adapted to enable the workman to connect the light units to the supporting frame at the point of installation rapidly and accurately.

It has been found in practice that the present invention enables municipal employees and others who install traffic control units to set the lights up at precisely the desired angles with little loss of time.

The present application is a division of my application filed October 16, 1951, under Serial No. 251,475, now abandoned.

The recited and other advantageous objects, which will appear from the drawings and from the description hereinafter, are accomplished by the structures of my invention, of which embodiments are illustrated in the drawings. It will be apparent, from a consideration of said drawings and the following description, that the invention may be embodied in other forms, and such other forms as come within the scope of the appended claims.

In the drawings:

Fig. 1 is a side elevational view of a traffic light holder embodying the invention.

Fig. 2 is an enlarged fragmentary vertical sectional view, taken on line 2—2 of Fig. 3.

Fig. 3 is an enlarged fragmentary horizontal view, taken on line 3—3 of Fig. 1.

Fig. 4 is a perspective view of one of the corner bracket sections embodying the invention.

Fig. 5 is a top plan view of a complementary bracket section,

Fig. 6 is a vertical sectional view, taken on line 6—6 of Fig. 5,

Fig. 7 is a partly fragmentary top plan view of a traffic light holder embodying another form of the invention, and

Fig. 8 is an assembled view of a corner bracket embodying the invention.

In Fig. 1, the traffic light units A and B are shown secured to the frame 10 which is horizontally connected to the pole 11, by means of suitable clamp members 12. A tie rod 13 may be secured at its opposite ends to the pole and frame as a supplementary or auxiliary means of connection. Pursuant to the present invention, one or more light units A, B may be secured to the pole parallel to or at an angle to the axial line a of the frame 10 (Fig. 3).

This end is attained by the utilization, pursuant to the invention, of corner brackets (29—32 inclusive, in Fig. 3) for connecting the traffic light units A, B to the frame. One or more "I" bars 20, 21 are slidably secured to the horizontal portions of the frame, the "I" bar 21

2

being adapted to connect the traffic light units at one end to the frame, the other ends of said units being connected to the outer end of the frame. By the present invention, the traffic light units are mounted on the frame in such fashion as to support only their own weight; that is, the traffic light units do not carry the weight of the frame or other parts of the traffic light holder. The "I" bars 20, 21 are provided with apertured ends 22, 23, 24, 25 to receive the horizontal frame 10, and are provided with set screws 26 (Fig. 2) or the like to fix the position of the bars on the frame. It will be appreciated that the bar 20 may be dispensed with entirely, pursuant to the invention, the bar 21 being used in connection with the invention, the bar 20 constituting simply an auxiliary strengthening device which may be dispensed with if so desired, and being so disposed along the frame as to attain that end. A pair of internally threaded horizontal frame arms 27, 28 are secured to the frame in spaced relation for connection of traffic light units thereto, one of said arms being secured, for example, to the "I" bar 21 while the other is secured to the outer end 10a of the frame.

The corner brackets of the invention are connected to said arms 27, 28 and to the light units A and B, as will be presently described. A description of one corner bracket will suffice for all, which are of identical construction. Reference is made to the bracket 29 (Fig. 3) which comprises the bracket halves or sections 33, 34, pivotally connected as at 35 (Fig. 8). The bracket section 33 comprises a stem 40 which may be externally threaded for engagement with the horizontal frame 27, and a cup portion 41 unitary with said stem and comprising parallel spaced flat side walls 42, 43, and the curved end walls 44, 45. The other bracket section, 34, is so constructed as to receive the section 33 and enable the same to be pivotally connected thereto as at 35, said bracket section 34 comprising a stem portion 48 which is preferably internally threaded as at 49 for engagement with the arm 36 of the light unit. A cup-shaped extension 50 is secured to the stem portion 48 and comprises the flat parallel side walls 51, 52 and the curved end walls 53, 54 which define an opening to receive the cup end 41 of the bracket section 33. The curved end walls 44, 45 of the first mentioned bracket section 33 define, with the stem portion 40 thereof, opposed shoulders 55, 56, which are adapted to engage the free edges of the end walls 53, 54 of the section 34, said end walls serving as stops for that purpose. The angle defined by the free ends of the end walls thus determines the extent of the complementary engagement therewith of the shouldered portions of the first mentioned section 33 and thus determines the limit of movement of the bracket sections relative to each other and therefore the limits of angular range to which the sections may be adapted for the purpose of properly aligning the light units A, B on the frame 10.

In operation, the workman would assemble the parts, as shown, for example, in Fig. 3, and then by tightening bolts 65, for example (Fig. 8), which may be passed freely through openings 67 in the section 34 for threaded engagement with the internally threaded apertures 68 in the sections 33, lock the parts at precisely the angular disposition desired. The arrangement shown in Figs. 4 and 8 enables the use of two short bolts which will be threaded into internally threaded apertures 68, 69, of the side walls 42, 43 of the bracket section 33. However, a single bolt might be used in place of the double bolt arrangement described, if so desired.

It will be appreciated that the arrangement above described is adaptable to a wide range of different angles. However, in an extreme case, as is illustrated for example in Fig. 7, where the angle at which the light unit B is

to be disposed is a large number of degrees from the axis of the unit A, one of the corner brackets of the invention may be used to secure an end of the unit B to the frame 10, the other end of said unit B being connected to the frame by an extended arm 61 which is secured at one end to arm 27, a bracket 62 being slidably disposed on the extended arm 61 at the point at which it is desired to fix the position of the traffic unit B. Set screws 63 or the like may be used to secure the bracket 62 to the arm 61 at that position. The bracket 62 may engage an arm 64 secured to the unit B in any desired or convenient manner, or may be otherwise connected to said unit for the purpose mentioned. It will be apparent that in the use of the form of invention illustrated in Fig. 7, one unit A could be secured to the frame in parallel relation thereto as by means of the brackets of the invention or by standard fittings S. The other unit B may be secured by utilizing one of the corner brackets of the invention to connect one end of the unit B, the other end of the unit B being secured to the extended arm 61 which defines an arc on a radius drawn from the pivot point 35 of the corner bracket 32. The invention is adapted to secure not only two light units A, B to the frame, but also may be used in other applications where it is desired to effect angular relations.

Having thus described my invention, what I claim as new and desire to secure by Letters Patent is:

1. A device for suspending a traffic light unit comprising a pair of generally straight parallel portions united at adjacent ends to form a generally U-shaped frame, means for securing the other ends of said parallel portions to a traffic pole so that said portions lie generally horizontal, a bar extending between and secured to the parallel horizontal portions of said frame and spaced from the united ends thereof, bracket members secured to the bar and to the united end of said frame and respectively secured to said unit to suspend the latter from said frame, each of said bracket members comprising a stem portion secured to and extending from the bar and the united end of the frame and a stem portion secured to and extending from one end of the light unit, complementary extensions on said stem portions, one of said extensions of each bracket member having substantially completely circular end walls secured to its stem portion and defining therewith shouldered portions, the extension of each of the other of said stem portions comprising a

5 pair of side walls and end walls connecting the side walls adjacent its stem portion and defining therewith an opening to receive the complementary extensions of the first-mentioned stem portions, the shouldered portions being adapted to contact the end walls of the second-mentioned extensions to limit movement between said complementary extensions, and means pivotally connecting together complementary pairs of said extensions.

2. A device for suspending a traffic light unit comprising a pair of generally straight parallel portions united at adjacent ends to form a generally U-shaped frame, means for securing the other ends of said parallel portions to a traffic pole so that said portions lie generally horizontal, a bar extending between and secured to the parallel horizontal portions of said frame and spaced from the united ends thereof, bracket members secured to the bar and to the united end of said frame and respectively secured to said unit to suspend the latter from said frame, each of said bracket members comprising a stem portion secured to and extending from the bar and the united end of the frame and a stem portion secured to and extending from one end of the light unit, complementary curved extensions on said stem portions, one of said curved extensions of each of said bracket members having an opening for reception of the complementary extensions of the other bracket member, each of said complementary extensions being slidably received and rotatable in its complementary first-mentioned curved extension for adjustment of the angular position of the light unit on the frame, and complementary means on the curved extensions for locking them in predetermined adjusted relationship.
